US00D368077S

United States Patent

[19]

Iino

[11] Patent Number: Des. 368,077

[45] Date of Patent: **Mar. 19, 1996

[54] ELECTRONIC COMPUTER

67297 2/1987 Rep. of Korea .

[75] Inventor: **Masaaki Iino**, Saitama, Japan

(List continued on next page.)

[73] Assignee: **Kabushiki Kaisha Toshiba**, Kanagawa, Japan

OTHER PUBLICATIONS

[**] Term: 14 Years

Sharp, May 19, 1974.

[21] Appl. No.: 36,086

Data General One Advertisement, Sep. 28, 1984.

[22] Filed: Mar. 13, 1995

Data General One, May 23, 1985.

[30] Foreign Application Priority Data

Data General One, Model 2J, May 20, 1987.

Sep. 30, 1994 [JP] Japan 6-29545

MultiSpeed E1 Model, May 10, 1988.

[52] U.S. Cl. D14/106

NEC, PC-99801 LV21, May 13, 1988.

FIG. 1 is a top, front and right side perspective view of an electronic computer showing my new design;
FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view thereof in closed position;

FIG. 9 is a right side elevational view thereof in closed position; and,
FIG. 10 is a top plan view thereof in closed position.

1 Claim, 5 Drawing Sheets
